UNITED STATES PATENT OFFICE.

ROLAND C. FAUST, OF INDIANA, PENNSYLVANIA.

DESIGN FOR A NEWSPAPER RACK.

Application filed September 30, 1921. Serial No. 504,478. Term of patent 3½ years.

To all whom it may concern:

Be it known that I, ROLAND C. FAUST, a citizen of the United States, residing at Indiana, in the county of Indiana and State of Pennsylvania, have invented a new, original, and ornamental Design for Newspaper Racks, as shown in the accompanying drawing and described in the following specification.

The figure represents a perspective view of a newspaper rack constructed in accordance with my invention.

I claim:

The ornamental design for a newspaper rack, as shown.

ROLAND C. FAUST.
